Victor J. Evans,
ATTORNEY

UNITED STATES PATENT OFFICE.

JULIAN GORDON KNIGHT, OF BROOKLYN, NEW YORK, ASSIGNOR TO NORMAN P. FINDLEY.

Fixture-Hanger

1,025,068.

Specification of Letters Patent. Patented Apr. 30, 1912.

Application filed July 8, 1910. Serial No. 570,979.

To all whom it may concern:

Be it known that I, JULIAN GORDON KNIGHT, a citizen of the United States, residing at Brooklyn, in the county of Kings 5 and State of New York, have invented new and useful Improvements in Fixture-Hangers, of which the following is a specification.

This invention relates to hangers for gas and other fixtures and its object is to provide a simple and substantial means which are adapted to be fitted in the ceiling of a building and have a threaded socket or nipple upon which may be screwed the fixture or any similar device which may be required in the ceiling at that point, as will be more fully described in the following specification, set forth in the claim and illustrated in the drawings, wherein:

Figure 1 is a sectional view through the ceiling of a room showing the device secured therein. Fig. 2 is a side elevation of the device ready for locating. Fig. 3 is a sectional view with the straps bent for location. Fig. 4 is a modified form. Fig. 5 is 25 a sectional view through same. Fig. 6 is another modified form.

The invention comprises a short socket or stud 10 threaded on the outside or inside so that an insulating joint 11 may be screwed 30 thereon, the said joint carrying the stem 12 of an electric light or other fixture 13. It is obvious that the fixture may be attached directly to the stud 10 and in order to provide for the safety of the electric current 35 and to prevent cross circuit which might otherwise prove dangerous, the connection 11 is provided. If thought advisable, the stud 10 may be of greater diameter and threaded on the inside where the fixture may 40 be secured therein by means of a non-conductive collar as shown in Fig. 6.

The stud 10 is preferably a short section of gas pipe threaded at one end and at the other end carrying the straps 14 which may 45 be riveted to the closed end of the pipe as shown in Figs. 4 and 5 or secured in the upper end by means of a cross pin 15. Various means may be adopted for closing the end of the stud 10 and securing to it the 50 straps. The straps 14 are bent at right angles to the stud and may be secured to the

rafters of the building or embedded in concrete arches and the dislocation of the stud thus prevented. The electric conduit 16 may be embedded in the ceiling and have its 55 outlets in a non-conducting box 17 from which the wires may pass down the fixture 12 to the bulbs and the upper end of the fixture may be provided with the canopy 18 to seal the joint 11, the box 17 and the wiring and give the fixture a finished appearance. It is obvious that the wiring may pass down the stud 10 where desired, provided that sufficient insulation is on the wire. This method of hanging may also be 65 provided in case it is necessary to hang pipes, conduits or wiring along the ceiling in which case a loop may be screwed to the lower end of the stud and considerable weight supported thereby. It is obvious 70 that the parts may be otherwise arranged and modified without departing from the essential features above described.

What I claim as new and desire to secure by Letters Patent is:

In combination, a pair of supporting bars arranged in contacting relation and with their upper ends disposed angularly to the lower ends and embedded in a ceiling, a member secured to the lower ends of said 80 bars and having external threads thereon, a flanged member having an opening to receive said first member and adapted to brace said first member to a ceiling and having wire receiving openings, a hollow member 85 threaded on said first member and provided with wire receiving openings, a fixture pipe threaded to said hollow member and adapted to receive wires extended through said hollow member and a shield having a contracted 90 lower end contacting with said fixture pipe and an upper end disposed outwardly of the flanged member adapted to contact with the ceiling and brace said fixture pipe 95 thereto.

In witness whereof I affix my signature in presence of two witnesses.

JULIAN GORDON KNIGHT.
